CASING PICK-UP ELEVATOR

Wesson W. Smith, Plainville, Kans.

Application March 14, 1938, Serial No. 195,798

6 Claims. (Cl. 294—106)

My invention relates to a casing pick-up elevator and has for its principal object a pair of hingedly connected jaws that will engage a pipe resting on a horizontal support and without raising the pipe for full engagement, the pipe being such as commonly used in oil fields and referred to as a casing, and means to lock the jaws to gripping engagement, the gripping tension of the jaws not interrupted by the weight of the load.

A further object of my invention is to provide a pair of gripping jaws hingedly connected so that the free ends will swing to and from each other and means carried by one of the jaws to lock them against outward movement when carrying a load.

A further object of my invention is to construct an inexpensive arrangement that is efficient and simple to operate and being locked in such a way that the carrying means is not inclined to open or close the jaws when carrying a casing or the like in a vertical position.

These and other objects will hereinafter be more fully explained, reference being had to the accompanying drawings forming a part of this specification and in which like characters will apply to like parts in the different views.

Referring to the drawings:

Fig. 1 is a view axial of the jaw members being locked on a casing.

Fig. 2 is a top or plan view of the jaws, the casing not shown.

Fig. 3 is a sectional view taken on line 3—3 in Fig. 2 showing the position of the locking means for the jaws in their closed position.

Fig. 4 is a similar sectional view to that of Fig. 3 but illustrating the jaws in an open position and the locking means as carried to permit rocking movement of the jaws.

Fig. 5 is a reduced side view of the elevator secured to a casing medially of its ends and broken away for convenience of illustration.

Fig. 6 shows the elevator carrying a casing vertically as gripped below the coupling.

Fig. 7 is an enlarged view of the jaw and locking means and a modified handle and pawl.

Fig. 8 is a plan view of Fig. 7.

My invention herein disclosed consists of a pair of jaws 1 and 2, said jaws arcuate in form and hingedly connected by interlapping ears 3, there being two pairs oppositely positioned, each of which are adjacent their respective ends of the jaws, as shown in Fig. 2, and rockable on a rod 4, each end of which pivotally connects its respective pair of interlapping ears.

Positioned on the corresponding end of each jaw is an ear 5 obliquely extending outward. Each ear has an aperture 6 to receive a cable 7 respectively, the cable being looped to receive a cable line secured thereto as hoisting means for the jaws, the line not shown in the drawings. On the outer side of jaw 1 and extending thereacross is a bar 8, each end portion of which has a right angle bend A, the ends of which seat on the back of the jaw as spacing means for the straight bar portion therefrom to receive an arcuate plate 9 slideable thereunder to engage on the outer side of each jaw when said jaws are in a closed position as shown in Fig. 1, locking the same against outward rocking movement and the said plate being secured for sliding engagement on the back of said jaws by said rod 4 coacting with the plate to avoid upward and outward movement of the free ends or tips of said jaws. The said plate is adapted to seat on jaw member 1 when moved to engagement with a lug 10 functioning as a stop in which position the jaws are free to open by rocking movement as above described.

Radially extending and being positioned near one side of the plate is a handle 11 as manipulating means and stop for the plate and the said handle may be modified as a securing means for the plate when said plate is moved to engagement upon each jaw. The securing means consists of a pawl 12 having a hook 13 on the free end thereof, the other end pivotally connected to said handle by a pin 14 by which means the pawl is free to rock upward when the hook strikes the edge of bar 8 and forced downward to engage on the opposite side of said bar as tensioned by a spring 15, the ends of which are seated in their respective sockets 16 and 17 and secured by pins 18 and 19 respectively. The said pawl is checked in its downward movement by a lug 20 carried by said handle and the said lug is means to raise the pawl from engagement when the handle is rocked in the direction of arrow B. The rocking movement will be across opening C in the plate at the lower extremity of the handle and the opposite movement of the handle will be restricted by its engagement as at D. It will be understood that the said handle is pivotally connected to the plate as at E between a pair of ears 21 integrally joined to the plate.

To operate the elevator, when raising a casing or the like, the jaws are opened as shown in Fig. 4, the spread of which is sufficient to permit a casing as shown by dotted lines F' entering the

jaws and being closed thereon as shown in Fig. 3 and locked to position by the said arcuate plate 9 after which the elevator is raised through the medium of the cable arrangement above described that may be actuated by motive or manual power, said power means not illustrated in the drawings. To release the elevator jaws the said plate is moved to its extremity upon jaw 1 as shown in Fig. 4 freeing said jaws to open, releasing or receiving its load, and such other modifications may be employed as lie within the scope of the appended claims.

Having fully described my invention what I claim as new and desire to secure by Letters 15 Patent is:

1. In a casing pick-up elevator, an elevator element of the class described comprising two arcuate jaws, each jaw of a desired width and segmental portion of an arc and hingedly connected, the cavity of each confronting each other and the free ends rockable from each other to open the jaws and toward each other to a closed position, an arcuate plate slideably carried by one of said jaws and adapted to seat on the other jaw and means to equally position the plate on each jaw adjacent the hinge to lock the jaws in a closed position.

2. In a casing pick-up elevator, a pair of arcuate jaws, each having a pair of ears outwardly extending and adapted to interlap and being apertured in axial alignment, a rod to engage in the apertures and extending from one pair of ears to the other and spaced from the body of the jaws, an arcuate plate coinciding with the arc of the jaws and being carried by one of said jaws slideable thereon and between said rod and body of the jaws to avoid outward movement from said jaws when engaged approximately equal on each thereof by which means said jaws are locked against outward rocking movement.

3. In a casing pick-up elevator, a pair of arcuate jaws, each having a pair of ears outwardly extending and adapted to interlap and being apertured in axial alignment, a rod to engage in the apertures and extending from one pair of ears to the other and spaced from the body of the jaws, an arcuate plate coinciding with the arc of the jaws and being carried by one of said jaws slideable thereon and between said rod and body of the jaws to avoid outward movement from said jaws when engaged approximately equal on each thereof by which means said jaws are locked against outward rocking movement, an apertured ear outwardly extending and positioned on corresponding ends of each jaw medial thereof with respect to the arc, said ears adapted to receive a cable in their respective apertures as manipulating means therefor.

4. In a casing pick-up elevator, an elevator element of the class described comprising two arcuate jaws, each jaw of a desired width and

segmental portion in width of an arc and hingedly connected, the cavity of each confronting each other and the free ends rockable from each other to open the jaws and toward each other to a closed position, a bar extending across one of the jaws, spaced from the hinge and in parallelism with the axis of the arc, the ends of said bar turned toward the back of the jaw to space the bar therefrom, said jaw having a lug radially extending from its back and positioned on the edge opposite the hinge, an arcuate plate slideably carried on the back of the jaw to which said bar is secured and slideable thereunder and stopped by the lug, the plate having a handle radially extending and secured to its edge adjacent the lug, the handle to impinge with the edge of the bar functioning as a stop for said plate as it seats equally on the back of each jaw to lock said jaws against outward rocking movement.

5. In a casing pick-up elevator, an elevator element of the class described comprising two arcuate jaws, each jaw of a desired width and segmental portion of an arc and hingedly connected, the cavity of each confronting each other and the free ends rockable from each other to open the jaws and toward each other to a closed position, a bar extending across one of the jaws, spaced from the hinge and in parallelism with the axis of the arc, the ends of said bar turned toward the back of the jaw to space the bar therefrom, said jaw having a lug radially extending from its back and positioned on the edge opposite the hinge, an arcuate plate slideably carried on the back of the jaw to which said bar is secured and slideable thereunder and stopped by the lug, the plate having a handle radially extending and secured to its edge adjacent the lug, the handle to impinge with the edge of the bar functioning as a stop for said plate as it seats equally on the back of each jaw to lock said jaws against outward rocking movement.

6. In a casing pick-up elevator, an elevator element of the class described comprising two arcuate jaws, each jaw of a desired width and segmental portion of an arc and hingedly connected, the cavity of each confronting each other and the free ends rockable from each other to open the jaws and toward each other to a closed position, an arcuate plate slideably carried by one of said jaws, means to retain the plate to sliding engagement on one of the jaws, a handle rockably carried by the plate and a spring tensioned pawl rockably carried by the handle, the pawl and handle to engage with the said plate retaining means to lock the jaws in their closed position as retaining and releasing means for an oil well casing or the like.

WESSON W. SMITH.
